UNITED STATES PATENT OFFICE.

FREDERICK GOELER, OF ALAMEDA, CALIFORNIA, ASSIGNOR TO EMMA A. GOELER,
OF ALAMEDA, CALIFORNIA.

SHEET-METAL-BENDING MACHINE AND METHOD OF TREATING THE SAME.

Application filed August 25, 1921. Serial No. 495,375.

To all whom it may concern:

Be it known that I, FREDERICK GOELER, a citizen of the United States, residing at Alameda, in the county of Alameda and State of California, have invented new and useful Improvements in Sheet-Metal-Bending Machines and Methods of Treating the Same, of which the following is a specification.

10 This invention relates to improvements in sheet metal bending machines of the type described in Letters Patent of the United States, Nos. 1,131,055 and 1,162,050, granted to me March 9, 1915 and November 30, 15 1915, respectively.

15 The invention has particular reference to improvements in the bending members or jaws of the machines of the character described and the primary object is to provide a bending member or jaw which will have maximum strength and durability and not be subject to disruption or warping or bending during the bending operation.

20 In bending machines of the character described in the patents above mentioned, the bending jaw or plate is relatively long and is hinged or pivoted at its ends to a frame, whereby relatively wide or long piece of sheet metal to be bent may be inserted between the hinges or pivots. In machines of 25 this type it is not possible to use any other means of connection between the bending plate or jaw and the frame other than the means at the ends of the plate and for this reason, the jaw plate is apt to warp or bend or buckle intermediate of its ends and when this occurs a defective bend in the sheet metal is produced and in some instances the bending operation is prevented entirely.

30 The particular object of the present invention is to provide a method of forming and strengthening or reinforcing a bending plate or jaw of a novel structure, so that the plate or jaw will not be subject to warping or becoming disrupted when in use. The invention also includes means for correcting any disruption or warping in the plate, should the same occur to a slight degree, after the plate is fixed to the machine.

35 The invention possesses other features and advantages some of which, with the foregoing will be set forth at length in the following description where I shall outline

in full that form of the invention which I have selected for illustration in the drawings accompanying and forming a part of the present specification. In said drawings I have shown one form of the construction 60 of my invention, but it is to be understood that I do not limit myself to such form since the invention as expressed in the claims may be embodied in a plurality of forms.

65 Referring to the drawings:

Figure 1 is a front elevation of a sheet metal bending machine constructed in accordance with the present invention.

Fig. 2 is an enlarged rear elevation of 70 the bending jaw or plate forming the particular part of this invention.

Fig. 3 is a vertical sectional view, taken on line 3—3 of Fig. 2.

Fig. 4 is an enlarged fragmentary sectional view of the bending plate or jaw and the work holding or clamping means with which it cooperates, showing a piece of sheet metal to be bent in position for bending, in dotted lines and the manner 80 of use of the angle bar on the bending member.

Fig. 5 is a fragmentary perspective view of the bending plate or jaw showing the slide member used during the process 85 or method of strengthening the plate or jaw.

Fig. 6 is an edge elevation of the plate or jaw showing the same as it would appear when being treated to reinforcing and strengthening the same.

90 In carrying out the present invention an elongated steel plate of substantially rectilinear outline is reinforced by riveting upon the back thereof near to its upper edge a T bar. After this reinforcing element is secured to the back of the plate, the plate is placed upon a suitable work table or supported upon a bar or mandrel and pressure is applied by any suitable means to the ends of the plate so as to 100 cause the plate to assume an arcuate form due to the position of the mandrel upon which the plate rests. The plate is held in this arcuate or bent shape by any suitable means and is next treated so that it will, 105 upon removal of said holding means, maintain a curved or arcuate shape. In order to cause the plate to have a permanent bend or curve, I preferably place upon the one side of the angle of the T bar, a solid, 110

paratively heavy metal block or rail and then with the sledge or other suitable heavy instrument, strike the vertical member of the T bar throughout the length thereof, 5 at intervals, so as to stretch the metal of the bar. By striking the T bar, preferably with a sharp pointed heavy instrument, the metal is stretched so that when pressure is released from the ends of the plate, the plate 10 will have a permanent curve or arcuate form. A straightening or adjusting means is attached to the plate and before the bending operation is preferably in the form of a rigid V-shaped bar or rod secured at 15 its ends to the end portions of the plate with the apex of the V disposed below the lower edge and centrally of the ends of the plate. An adjusting bolt with a nut is adjustably secured to the lower edge of the 20 plate and when operated exerts a pressure upon the V rod such that the plate will tend to straighten out. To make the plate suitable for use, the adjusting means is operated so that a strain is placed upon the 25 ends of the plate such as will cause the plate to straighten out. When the plate is straight and presents a flat outer or bending face, it is then attached to the machine and is ready for use. Due to the treatment 30 aforementioned, the plate is under such tension that it possesses maximum inherent strength and rigidity such as will withstand severe bending strains and will not be subject to buckling or bending.

35 Referring to the drawings, 1 designates a preferably horizontal table or supporting structure mounted upon suitable legs 2 and supporting work holding means which comprises jaws 3 and 4 which latter are located 40 one above the other in a horizontal plane so as to leave a space for the accommodation of pieces of sheet metal to be bent, as shown at 5 in Fig. 4. In connection with the table and work holding means including the jaws 3 and 4, there are provided 45 suitable bracing and securing devices 6 and means of adjustment 7 for the jaws. This means is fully described in Letters Patent hereinbefore referred to and need not be 50 described in detail.

55 Mounted upon the table 1 is a bending jaw or plate 8 of substantially rectilinear outline and which normally depends from a point substantially level with the jaw 4. The plate 8 is pivoted or hinged by suitable means as at 9 at its upper end edges to the table 1 with its inner side close to the forward edge of the jaw 4 and its upper edge flush with the upper surface of said jaw, 60 as shown particularly in Fig. 4. Suitable means 10 is provided for swinging the plate on its pivots or hinges so as to cause bending of the sheet metal plate 5.

65 The plate or jaw 8 is constructed of high grade steel and upon its rear face adjacent

its upper edge there is riveted a straight reinforcing element 11, preferably in the form of a T bar, the ends of which terminate a few inches short of the ends of the plate.

To provide for reinforcing the plate for heavy bending, the outer face thereof adjacent its upper edge is provided with a longitudinal countersink or recess 12 in which is removably mounted a flat plate 13, 70 as shown in Figs. 3 and 4. The outer face of this plate is substantially flush with the outer face of the plate 8 and the upper edge of the plate is flush with the upper edge of the plate 8. To further strengthen the jaw 75 an angle bar 14 may be removably screwed to plate 13 with the outer face of one angular portion 15 disposed flush with the outer edges of the plates 8 and 13, as shown in Fig. 4. Bolts 16 are passed thru the angle bar and plate 13 so as to removably secure 80 these parts together and similar bolts 16' pass thru the bar 14, plates 13 and 8, to removably secure the bar and plate to the jaw. Thus, it will be seen, that in bending 85 heavy sheet metal plate, the upper surface of the angle bar portion 15 and upper edges of the plates 13 and 8 bear directly upon the sheet metal to be bent. The angle bar 14 provides a relatively large surface to engage the plate to be bent and in this way 90 prevents localization of the strains and stresses upon the bending plate 8. In certain kinds of bending work, the bar 14 and plate 13 must be removed and this leaves 95 only the narrow edge of the plate 8 exposed for engagement with the work. Also in some instances it is only desirable to remove the angle bar and utilize the upper edges of the plates 13 and 8 to bear upon the work. When both the bar 14 and plate 13 are removed, the comparatively narrow edge of the plate 8 would be subject to bending or buckling under severe strains, were 100 it not for the treatment of the plate as hereinbefore described, to prevent this buckling and bending tendency. Also when only the bar 14 is removed and the plates 13 and 8 are 105 brought into use, the tendency of the plate 8 to buckle or bend is present and the treatment of the plate to give it natural inherent strength prevents the buckling or bending thereof. Thus, it will be seen, it is not 110 mainly when the elements 13 and 14, or particularly the element 14, is removed from the bending plate, that the necessity of having a plate treated with the method hereinbefore described, becomes apparent.

115 As a means for correcting the alinement of the plate 8 and for placing the same under such tension that it will have maximum strength and durability, I employ a heavy substantially V-shaped bar 17 the ends of which are flattened as at 18 and riveted 120 as at 19 to the end portions of the plate 8. 125

The apex of the V bar is disposed centrally of the ends of the plate and beneath the lower edge thereof, as shown in Figs. 1, 2 and 3. A bolt 20 is vertically adjustably mounted in a keeper member 21 riveted as at 22 to the rear face of the plate 8 centrally of the ends of the plate and near the lower edge thereof. The head of the bolt is slotted as at 20' and receives the apex 10 portion of the V bar 17, in the slot. A nut 23 is adjustable upon the eye bolt with its upper face bearing upon the member 21. By turning the nut 23 so as to extend the bolt downwardly a strain will be placed 15 upon the plate 8 such as will tend to correct any curvatures thereof.

As shown in Figs. 5 and 6, the plate or bending jaw 8 is treated so as to have maximum inherent strength and durability. 20 After the flange of the T bar is secured to the rear face of the plate, the plate is placed with the rear side uppermost so that the central portion thereof will rest upon a bar or mandrel 25. The bar or mandrel is supported upon a work bench or other support. 25 Pressure is applied by any suitable means, not shown, to the end portions of the plate so that the entire plate is bent into a curved or arcuate form, as shown in Fig. 6. The plate is held in this bent position by the means referred to and while thus held a block or bar of solid metal, shown at 26 in Fig. 5, is placed upon the reinforcing element 11 so as to bear against the vertical or 30 upstanding portion of said element. The vertical portion is then struck a series of sharp blows with a heavy sharp edged hammer or sledge, (not shown), upon the face thereof opposite that engaged by the member 26. This striking of the vertical portion is effected at slightly spaced points throughout the length thereof and for such a time that the metal of the member 11 will be stretched and the plate will have a permanent 35 bend or arcuate form. After hammering of the member 11 the desired extent, the pressure means is removed from the ends of the plate and the plate has a permanent bend longitudinally. The straightening of 40 the plate is accomplished by adjusting the nut 23 so that the bolt 20 will produce a pull upon the V bar 17. The V bar 17 when thus acted upon causes the plate to straighten and when the plate is thus straightened it is under such tension that it is better able to 45 withstand strains during the bending operation of the machine and not apt to become warped or to buckle.

In the operation of the bending machine, 50 the piece of sheet metal, as shown at 5 in Fig. 4, is placed between the jaws 3 and 4 so as to engage the angle iron 14 and plate 13, or when the bolts thru the bar or plate 13 are removed, will engage the plate 8, and 55 the mechanism 10 is then operated to swing

the plate upwardly. Upon movement of the plate the bending of the sheet metal will take place at the point where the outer edges of the jaws 3 and 4 and inner edge of the plate 8 are located. It is apparent that various bending operations may be carried out with mechanism of the character described and it is not thought necessary to go into detail as to this. The main feature of this invention is the novel form of bending jaw 75 or plate, particularly the method of treating the same so as to render it capable of withstanding severe bending strains when in use.

I claim:

1. In a sheet bending apparatus, means for holding material to be bent, a bending plate arranged so as to be moved in engagement with the material to be bent to effect the bending of the material, said bending plate 85 having a permanent curve in one direction and means on said plate for straightening the same so as to place said plate under tension.

2. The method of treating the bending 90 member of a sheet metal bending machine, which bending member comprises a relatively long metal plate, which consists in bending said plate so as to produce a permanent longitudinal curvature therein and then straightening the said plate to remove the longitudinal curvature so as to place the plate under tension.

3. The method of treating the bending 100 plate of a sheet metal bending machine so as to render the same highly resistant against bending strains, which consists in securing a reinforcing element to one side of the plate, producing a permanent curvature longitudinally in the plate and reinforcing element and then straightening said plate to remove the curvature thereof.

4. The method of treating a bending plate 110 or member of a sheet metal bending machine so as to render the same highly resistant to bending strains, which consists in mounting a reinforcing element on the plate so as to cause the plate and reinforcing element to maintain a given bend or curve then straightening said plate and reinforcing element.

5. In a sheet metal bending machine, a frame, means on the frame for holding sheet metal in position to be bent, a bending plate attached at its ends to the frame so as to move with relation to the holding means, means for moving said plate while the same is engaged with the material to be bent, such plate having a normal tendency to curve longitudinally and means carried by the plate for correcting a longitudinal curvature thereof and for maintaining the plate in straight form.

6. In a sheet metal bending machine, a 130 frame, means on the frame for holding sheet

- metal in position to be bent, a bending plate attached to the frame so that it may be moved in engagement with material to be bent, means for moving said plate to effect 15
5 bending of the sheet metal, said plate having a normal tendency to curve or bend longitudinally and means carried by the plate for correcting said tendency and maintaining the plate in straight form.
10 7. In a sheet metal bending machine, a frame, means on the frame for holding sheet metal in position to be bent, a bending plate attached to the frame so that it may be moved in engagement with material to be

bent, means for moving said plate to effect 15 bending of the sheet metal, said plate having a normal tendency to curve or bend longitudinally and means carried by the plate for correcting said tendency and maintaining the plate in straight form, which means 20 comprises a bar secured at its end to end portions of the plate and having a mid portion disposed below the lower edge of the plate, means carried by the central portion of the plate for transmitting a force to said 25 bar such as will tend to straighten the plate and remove any curvature thereof.

FREDERICK GOELER.
